FIXTURE SWITCH

Carl M. Petersen, Trenton, N. J., assignor to
Circle F Mfg. Co., Trenton, N. J., a corporation
of New Jersey

Application May 18, 1932. Serial No. 612,105

8 Claims. (Cl. 298—63)

This invention relates to switches and more particularly to a novel switch mechanism adapted for use as a canopy switch although having general application to other electrical fixtures such as table lamps or the like.

One of the objects of the invention is to provide a switch construction of maximum simplicity with consequent economy of manufacture, thereby meeting the requirements of installations which 10 demand a safe, reliable and yet inexpensive switch construction.

A further object of the invention is to provide a construction embodying only two major parts, namely, a base and a cap which are telescopically 15 related in such a way that the manipulation of the cap serves to operate the switch, thus greatly simplifying the construction from the standpoint of manufacture, as well as its manipulation in practical use and eliminating parts which are 20 likely to easily get out of order.

With the above and other objects in view which will more readily appear as the nature of the invention is better understood, the same consists in the novel construction, combination and arrangement of parts hereinafter more fully described, 25 illustrated and claimed.

A preferred and practical embodiment of the invention is shown in the accompanying drawing, in which:—

30 Figure 1 is a vertical sectional view of the improved switch construction.

Figure 2 is a horizontal cross sectional view taken on the line 2—2 of Figure 1.

Figure 3 is a bottom plan view of the cover carrying the switch contacts.

Figure 4 is a detail view illustrating one form of application of the invention.

Figure 5 is a view illustrating the various parts separated prior to assembly.

Figure 6 is a perspective view of one of the terminal contacts.

Similar reference characters designate corresponding parts throughout the several figures of the drawing.

45 Referring to the drawing, it will be observed that the invention includes in its organization, a base designated generally as A and a cap B telescopically related to the base to form a switch chamber. The cap B is operatively connected to the base A for rotatable movement by a suitable fastening C.

The base A is provided with a shank or stem portion A' for receiving the wires W and also carrying a support engaging member designated generally as D.

The said base is provided at one side with an 50 upstanding boss 1 formed with sockets or recesses 2 for receiving wire terminal contacts 3, and is also provided with the wire threading openings 3a. The contacts 3 are preferably of spring metal 55 and have their free ends disposed toward the periphery of the base while their inner ends are looped or formed with an eye portion 4 for embracing the ends 5 of the wires W which are of the usual insulation covered type except for the 60 portion thereof which is held within the loop or eye 4. These wires are led through the openings 3a which communicate with the grooves or channels 6 formed in the stem or shank A, and, as shown in Figure 1, the insulation thereof is compressed by the support engaging member D so as 65 to hold the wires in place.

The cap or cover B is preferably recessed at 70 one side to provide a flange or skirt portion 7 which telescopes over the boss 1 and a portion of the base itself thereby completely to house the 75 switch mechanism. The interior of the cap or cover may be provided with a boss 8 thereby conveniently to center a metallic bridging conductor member 9 having a central opening to fit 80 over the boss and provided at its outer ends with the switch contacts 10—10. The inside face of the flange 7 of the cover is formed with a plurality of ratchet faces 11—11 and 12—12, the former being covered by the switch contacts 85 10—10 and the latter providing insulating faces which receive the terminal contacts 3 when the circuit is broken. With the arrangement described it will be apparent that the cap or cover B not only constitutes the operator or actuator 90 of the switch mechanism, but also, the ratchet faces 11 and 12 and the intervening shoulder portions, provide the required quick make and break of the electrical circuit as the cover is moved or propelled intermittently.

As will be observed from Figures 1 and 3, the metallic conductor member 9 of the cover is effectively protected from the wire terminals 3 by the insulating disk 13 which conforms in shape 95 to the interior of the bottom of the cap recess.

The support engaging unit D preferably consists of a ring 14 having a flange 14a which surrounds the shank A' of the base and is exteriorly threaded as indicated at 15 to receive the clamping nut or collar 16. This construction permits of fitting the device to the support by merely placing the unit D in the opening of the support and then subsequently applying the nut or collar 16 to the threads 15 and moving the same 105 110

into clamping relation to the support designated generally as S.

- The base A and its cover B are preferably made of molded insulating material with the constructional features heretofore indicated, and in practice the wires W fitted with the terminal contacts 3 are preferably led through the wire threading openings 3a of the base so as to position the terminal contacts 3 in the sockets 2. 5
- 10 As previously indicated, the application of the support engaging means, particularly the ring 14 compresses the insulation on the wires W and thus serves to hold them in place prior to the fitting of the cap or cover B thereto. Thus, it 15 will be apparent that the assembling of the terminal contacts with reference to the base may be expeditiously effected and the cap or cover B may then be applied and held in place by the fastening C. 20
- 25 In use, it is only necessary to rotate the cover B to effect the desired make and break of the electrical circuit. When the contacts 10-10 engage the contacts 3-3 as shown in Figure 2 the circuit will be completed through the metallic conductor bridge member 9. On the other hand, when the cover is moved a quarter turn, the contacts 10-10 will be moved away from the contacts 3-3 and the latter will rest against the insulated ratchet faces 12-12 of the cover. 30

The circuit is thus broken but a subsequent quarter turn will reestablish the circuit. Without further description it is thought that the features and advantages of the invention will be readily apparent to those skilled in the art, 35 and it will of course be understood that changes in the form, proportion and minor details of construction may be resorted to, without departing from the spirit of the invention and scope of the appended claims.

40 I claim:

1. A fixture switch comprising an insulating base having a central upstanding boss portion, line wire contacts fitted in said boss portion, a rotatable cover telescopically fitting over the boss portion, and a conductor member carried at the inside face of the cover top and having its end portion adapted to engage the line wire terminal contacts on the base in certain positions of the cover. 45
- 50 2. A fixture switch comprising an insulating base comprising a body having a shank portion at one side thereof and a boss at the other side, line wire passages in the said body, line wire terminal contacts mounted edgewise in the boss, a cover telescopically fitting over said boss, a series of ratchet faces formed on the inside of the cover, a conductor member carried by the cover and comprising a body portion having an end thereof lying against certain of said ratchet faces, and means for rotatably mounting the cover on the base. 55
- 60 3. A fixture switch comprising an insulating base having a mounting shank at one side thereof and a boss at the other side thereof, line wires receiving passages formed in the shank and

body, flat contact springs mounted edgewise on the body in said boss and adapted to be connected with line wires arranged in said passages, and a cover including a top and flange telescopically fitting over the boss, ratchet faces formed on the inside wall of the flange of the cover, a bridging conductor member carried at the inside face of the top of the cover and having a contact portion located at a ratchet face, and means for rotatably mounting the cover on the base. 80

4. In a fixture switch, an insulating base, line wire contacts on the base, a cover rotatably mounted on the base and telescopically related therewith, a bridging conductor member carried at the inside face of the cover and having terminal portions adapted to engage and disengage with said line wire contacts on the base, and an insulation member overlying the portion of said bridging contact intermediate the ends thereof. 85

5. A fixture switch including an insulating base having a shank portion at the outer side, line wire contacts carried on the inside of the base, a cover rotatably mounted over the inner side of the base and having contact means cooperating with said line wire contacts, a tubular holding member surrounding said shank, and a clamping member engaging said tubular holding member to secure the switch to a support. 90

6. A fixture switch including an insulating base, a tubular mounting member attached to the insulating base, line wire contacts mounted at one side of the base, a rotatable cover actuating a switch contact for cooperating with the line wire contacts, electrical conductors attached to the line wire contacts and passing through the tubular mounting member, and a clamping element engaging said mounting member to secure the insulating base to its support. 100

7. A fixture switch including an insulating base having line wire receiving passages, relatively fixed contacts mounted on one side of the base, a cover rotatably mounted on the base and carrying a contact for bridging said relatively fixed contacts, line wires led through said passages and connected to said relatively fixed contacts, and fixture attaching means carried by the base, said means including a tubular member fitted over the portion of the insulating base opposite the cover and also having the line wires passing therethrough, and a clamping member engaging the tubular member to secure the base to its support. 110

8. A fixture switch comprising an insulating base having line wire passages therein, line wire terminal contacts mounted on the base, a cover fitted to said base and housing said contacts, a ratchet formed on an inside wall of the cover, a conductor member carried by the cover and comprising a body having portions thereof engaging said ratchet, and means for rotatably mounting the cover on the base to permit the conductor member to alternately engage and disengage the contacts on the base. 120

CARL M. PETERSEN. 14
